UNITED STATES PATENT OFFICE.

CHARLES W. T. DAVIES, OF NEW YORK, N. Y.

CUFF-LINK AND THE LIKE.

1,088,809.

Specification of Letters Patent.

Patented Mar. 3, 1914.

Application filed February 26, 1913. Serial No. 750,808.

To all whom it may concern:

Be it known that I, CHARLES W. T. DAVIES, a subject of the King of Great Britain, residing at New York, county of New York, 5 and State of New York, have invented certain new and useful Improvements in Cuff-Links and the like, of which the following is a specification.

This invention relates to improvements in 10 cuff links and the like, and has for its object to devise a form of cuff link, more especially for stiff cuffs, which shall be free from the disadvantages of such articles as hitherto adopted.

15 Heretofore most cuff links have been made of such a form that it is necessary to distend and strain to a considerable extent the buttonholes of the articles in connection with which the links are employed when inserting 20 or removing them, with the result that beside being a tedious and difficult operation, it has subjected the buttonholes to considerable soiling and rough usage, while the chain, bar or other member connecting the two end 25 members of the links has been free to shift along and therefore chafe the buttonhole, whereby the wear of the latter is further increased and the fore-edges of the cuff or the like are not held in constant symmetrical 30 relationship. On the other hand to obviate the above defects, other cuff links have been constructed in separate parts, connected together by joints, pivots, hinges, levers, etc., all resulting in more or less complicated articles, easily broken or disarranged.

35 The object of the present invention is to provide a novel cuff link which shall overcome all the above difficulties and disadvantages, and the invention consists, broadly, 40 in a cuff link or the like comprising an intermediate connecting portion provided at its ends with two side wings or lug-like members adapted to slide easily in and out of the buttonholes, the members which remain 45 in the buttonholes being sized to occupy substantially the full length of said buttonholes, and hold the two sides of the cuff safely in unvarying symmetrical relationship, without chafing or fraying the buttonholes—all being performed by a simple, and 50 preferably one-piece, article of bent metal or the like.

In the accompanying drawings: Figure 1 represents in plan a blank from which the 55 form of link shown in Figs. 2 to 6 may be reconstructed; Figs. 2 and 3, respectively, a

front elevation and rear perspectives showing the form of cuff link constructed from the blank shown in Fig. 1; Figs. 4 to 6 are, respectively, front, side, and plan views 60 illustrating the cuff link in position in a cuff; Figs. 7 to 11 are end views illustrating modified forms of the cuff link, while Figs. 12 to 18 are plan views showing other modified forms of the intermediate connecting 65 portions; and Figs. 19 to 23 illustrate in side elevation, some convenient designs of end wings which may be adopted.

In carrying my invention into effect in 70 what I consider the most advantageous manner, I take any suitable form of blank formed from sheet metal or other suitable material, such as that illustrated, for example, in Fig. 1, comprising an intermediate portion *a* with two side wings or members *b* and *c*, the latter being adapted to be bent on the dotted lines so as to form in connection with part 75 *a*, an angle of approximately 90° (Figs. 2 and 3), although it is to be understood that the angle may be more or less, as desired. 80 Though the intermediate portion *a* is, in this case, shown as integral with the wings *b* and *c* and both rigid and solid, it need not necessarily be any of these, but it is essential that, immediately at its junction with the 85 wings, it should be connected with the wings on either side for a distance not less than substantially the full length of the buttonholes with which the links are to be employed. The wings may be joined to this 90 intermediate connecting portion *a* at any angle from front to rear, but preferably so directed and spaced apart as to conform with the average more or less triangular space 95 inclosed between the two front edges *A'* of the resilient cuff *A* (Figs. 4, 5, 6) when brought together. This intermediate portion may be rigid or flexible, but must, as shown in all cases, be cross connected with the side wings from their foremost to their 100 hindmost upper edges, which again should be at this point of substantially the full length of the buttonhole, as already mentioned and further pointed out below.

105 Referring to Fig. 1, the side wings *b* and *c* are also at their connection with the intermediate portion *a*, of substantially the full length of the buttonhole through which they are to be inserted, as shown more clearly in Figs. 4 and 5, where the buttonholes appear 110 at *A''*. The wing portions *b*, *c*, which may be considered as those portions which re-

main outside of the buttonhole when the links are properly set and adjusted, may be concave, convex or rectilinear as in the various examples illustrated, and their lower ends *b'* may, if desired, be bent slightly outward and upward for the purpose of facilitating their entry into the buttonholes. They should, preferably, be made of comparatively thin and smooth material and in all forms are shown provided with raised portions or projections *d* along their upper edges at or immediately adjacent to their junction with the connecting portion *a*, and so situated as to lie just outside the buttonholes and immediately against the outer surface of the cuff after insertion. These projections *d* provide buttresses for security against the buttonholes of a resilient cuff spreading outward over the side wings *b, c*. They may be provided in the form of a hollow bend, solid bead, or embossing on the outer surface of the wings, and may be directed vertically, horizontally or diagonally, as toward either the wings or connecting portion. They should preferably, as shown, be of a rounded or curved rather than abrupt, form so as to permit of their rolling within and without the buttonholes easily without fraying them, and rise approximately say one-eighth of an inch in elevation from the plane of part *a*. It is to be understood that any form of wings may be employed with any connecting portions as illustrated, and I may provide any shape or ornamentation for my improved cuff links, and any suitable material such as sheet metal, celluloid, bone, ivory, shell or other material, engraved, stamped, embossed, cut-out, enameled or otherwise suitably treated or ornamented may be selected for its construction. The downward length and shape of the wings is immaterial, the area of their surface depending upon what may be the preferred design employed, if any.

The members forming my links may be

assembled and put together in any suitable manner so long as the result conforms with the spirit of my claim. I may, however, repeat that of all the forms shown, I consider the integral one-piece form constructed out of bent metal to be the most advantageous, and the preferred one, for many reasons. If so constructed, the article may be cut, shaped, bent and stamped in one operation, thus saving the cost and time of assemblage of parts and allowing a greater margin to be spent on its ornamentation as an attractive but economical article. To the user also, an article of the kind made in one solid piece is much more efficient than one comprising several parts, thus avoiding the frequent breaking or separation of the parts which is so common a fault with cuff links, owing to the strain to which they are subjected. Also, it is much easier to insert into stiffly starched buttonholes an article having a broad and solid connecting portion, as such a form provides a firm thumb leverage not obtainable when the connecting portion is in the form of a flexible chain or narrow bar.

Having thus described my invention, what I claim as new and desire to secure by Letters Patent, is:—

A cuff link having a connecting member, side wings rigidly connected thereto which are disposed transversely in relation to said connecting member and arranged in converging planes extending in the direction of the length of the connecting member, said wings being provided with slight or low raised parts or ridges extending in converging relation the full length of the wings where they join the connecting member.

In testimony whereof, I hereunto affix my signature in presence of two witnesses.

CHARLES W. T. DAVIES.
